UNITED STATES PATENT OFFICE

169,671

SIGN

Frank Homme, Minot, N. Dak.

Application January 6, 1953, Serial No. 23,039

Term of patent 14 years

(Cl. D72—1)

To all whom it may concern:

Be it known that I, Frank Homme, a citizen of the United States, residing at Minot, in the county of Ward and State of North Dakota, have invented a new, original, and ornamental Design for a Sign, of which the following is a specification, reference being had to the accompanying drawing, forming part thereof.

The single drawing figure is a front elevational view of a sign, showing my new design.

The dominant features of my design are shown in solid lines. The sign is of a conventional thickness and the back thereof is plain.

I claim:

The ornamental design for a sign, as shown and described.

FRANK HOMME.
